STOP COCK KEY OR SIMILAR ARTICLE

James M. Sexauer, Harrison, N.Y., assignor to
J. A. Sexauer Mfg. Co., Inc., White Plains, N.Y.,
a corporation of New York

Filed Jan. 3, 1967, Ser. No. 5,265

Term of patent 14 years

(Cl. D54—16)

FIG. 1 is a perspective view of a stop cock key or similar article, showing my new design;

FIG. 2 is a top elevational view thereof;

FIG. 3 is an end view thereof;

FIG. 4 is another end view thereof;

FIG. 5 is another end view thereof; and

FIG. 6 is another end view thereof.

I claim:

The ornamental design for a stop cock key or similar article, substantially as shown.
